Primary Examiner — Eric Goodman*Assistant Examiner* — Amy Wierenga**(57) CLAIM**

The ornamental design for a compact ball seat downhole plug, as shown and described.

DESCRIPTION

FIG. 1 is a perspective view of a compact ball seat downhole plug;

FIG. 2 is another perspective view of the compact ball seat downhole plug;

FIG. 3 is a left side plan view of the compact ball seat downhole plug;

FIG. 4 is a right side plan view of the compact ball seat downhole plug;

FIG. 5 is a front side plan view of the compact ball seat downhole plug.

FIG. 6 is a back side plan view of the compact ball seat downhole plug.

FIG. 7 is a top plan view of the compact ball seat downhole plug; and,

FIG. 8 is a bottom plan view of the compact ball seat downhole plug.
